(57) **CLAIM**

The ornamental design of an athletic and sports shoe, as shown and described.

DESCRIPTION

The patent or application file contains at least one drawing executed in color. Copies of this patent or patent application publication with color drawing(s) will be provided by the Office upon request and payment of the necessary fee.

FIG. 1 is a perspective view and partial front elevational view showing my new design;

FIG. 2 is a left side elevational view showing my new design;

FIG. 3 is a right side elevational view showing my new design;

FIG. 4 is a top plan showing my new design.

FIG. 5 is a rear elevational view showing my new design; and,

FIG. 6 is a bottom plan view showing my new design.

The shoe shown in FIGS. 1-6 is for a left shoe. The right shoe is a mirror image of the left shoe.
